UNITED STATES PATENT OFFICE

163,683

GUMMED LABEL DISPENSER

Aldo Ferrato, Pittsburgh, Pa.

Application July 8, 1950, Serial No. 11,019

Term of patent 14 years

(Cl. D74—1)

To all whom it may concern:

Be it known that I, Aldo Ferrato, a citizen of the United States, residing at Pittsburgh, in the county of Allegheny and State of Pennsylvania, have invented a new, original, and ornamental Design for Gummed Label Dispenser, of which the following is a specification, reference being had to the accompanying drawing, forming a part thereof.

Fig. 1 is a plan view of a gummed label dispenser, showing my new design;

Fig. 2 is a side elevational view;

Fig. 3 is a front elevational view; and

Fig. 4 is a front perspective view thereof.

I claim:

The ornamental design for a gummed label dispenser, as shown.

ALDO FERRATO.
